UNITED STATES PATENT OFFICE.

FRANK WATERS VAN NESS, OF MILWAUKEE, WISCONSIN.

WASHING-MACHINE.

1,207,820.

Specification of Letters Patent. Patented Dec. 12, 1916.

Application filed February 19, 1912. Serial No. 678,645.

To all whom it may concern:

Be it known that I, FRANK W. VAN NESS, a citizen of the United States, residing at Milwaukee, in the county of Milwaukee and State of Wisconsin, have invented certain new and useful Improvements in Washing Machines, of which the following is a specification, reference being had to the accompanying drawing, forming a part thereof.

10 The main object of this invention is to continuously and thoroughly wash and rinse clothing and the like, in batches or separate lots, without directly subjecting any batch or lot to the water with which others have 15 been washed.

It consists in the construction, arrangement and combination of parts as herein-after particularly described and pointed out in the appended claims.

20 In the accompanying drawing like characters designate the same parts in the several figures.

Figure 1 is a vertical longitudinal section on the line 1 1, Fig. 2, of a washing machine embodying the invention; Fig. 2 is a plan view of the same; Fig. 3 is an enlarged cross section on the line 3 3, Figs. 1 and 2; and Fig. 4 is a similar section on the line 4 4, Figs. 1 and 2.

30 The machine comprises a tank *a*, which is divided longitudinally by transverse partitions *b* into compartments *c*. The compartments *c* are subdivided transversely by longitudinal partitions *d* into washing compartments and plunger compartments, the latter communicating with the former below said partitions.

40 A foraminated clothes receptacle *e*, extending longitudinally through the tank *a* across the compartments *c* is mounted upon a rotary shaft *f*, having bearings at the ends of the tank *a*. This receptacle is preferably constructed in the form of a cylinder with spaced longitudinal slats *g* rounded on their inner sides and secured to and supported at intervals by circular bands *h*. At one end the head *i* of the clothes receptacle *e* is formed with an opening with which the lower end of a feed hopper *j* communicates. At the other end said receptacle is provided with a closed head *k*, and next to it with a discharge opening *l*. Between the feed and discharge openings said receptacle is provided with an internal spiral conveyer *m*, by which clothes are gradually transferred from its

feeding to its delivery end, where they are discharged through the opening *l* upon an endless conveyer and elevator belt *n*. The belt *n* is mounted on rollers *o*, the upper roller shaft being extended through the adjacent end of the tank *a* and provided with a gear *p* which meshes with and is driven by a gear *q* on an eccentric shaft *r* running lengthwise of the machine over the plunger compartments parallel with the shaft *f*. The machine is provided on one side at its discharge end with a hopper or receptacle *s*, into which the washed clothes are delivered by the belt *n*.

70 The shaft *f* is provided at one end with a ratchet wheel *t* and next to the ratchet wheel with a rocker arm *u* loosely mounted thereon and provided with a pawl *v* adapted to work with the ratchet wheel and intermittently and slowly turn the clothes receptacle *e*. The arm *u* is actuated by a rod *w* connecting it with an eccentric *x* on the shaft *r*, which is the driving shaft and is provided with a pulley *z*. The several 80 plunger compartments are provided with vertically reciprocating plungers *2*, connected as shown in Figs. 2 and 4, by rods and straps *3* with eccentrics *4* on the shaft *r*.

75 The several compartments *c* are preferably formed with hopper-shaped bottoms, as shown in Figs. 1, 3 and 4, the lowest parts of which are located directly below the clothes receptacle *e* and are connected by branch pipes *5* with a discharge pipe *6*, 90 the several branch pipes *5* being provided with valves *7*. An overflow pipe *8* opens from the end of the tank *a* next to the feed hopper *j*, preferably near the horizontal center of the clothes receptacle *e*. A hot water supply pipe *9* is provided with perforated spray branches *10* extending transversely over the clothes receptacle *e* above the two compartments *c* nearest the feed hopper *j*, and provided with valves *11*. A cold water supply pipe *12* has perforated spray branches *13* extending transversely over the remaining compartments *c* above the clothes receptacle *e* and provided with valves *14*. The last compartment *c'* at the discharge end of the tank contains the conveyer and elevator belt *n*, and has no plunger.

100 When the machine is quite long, the clothes receptacle *e* is or may be supported at intermediate points by rollers *15* journaled in brackets *16*, attached to one or

more of the partitions *b* and arranged to engage with one or more of the bands *h*.

In the operation of the machine, clothes are conveyed in separate batches or lots 5 through the hopper *j* into one end of the receptacle *e*, which with the spiral conveyer *m* being slowly turned gradually carries them over and across the several compartments *c* to the opening *l*, through 10 which they are discharged on the belt *n*. The belt *n* conveys and elevates them from the compartment *c* over one side of the tank *a* into the hopper or receptacle *s*.

The valves 7, 11 and 14 being adjusted to 15 keep the tank *a* filled with water to the level of the overflow pipe 8 and at the same time produce a substantial downward current through the several compartments *c* and their discharge connections 5, the clothes as 20 they pass over the several compartments are subjected to the action first of hot water and then of cold water, by which they are thoroughly rinsed. The hot water may be supplied with soap or other cleansing agents to 25 more effectively remove the dirt from the clothing or the like as it is conveyed through and over the first compartments. The plungers 2 cause the water in the several compartments except the last one, to pulsate 30 through the openings between the slats *g* and through the clothes or the like contained in the receptacle *e*, thereby effectively loosening and removing dirt, which is immediately carried off by the down flow of water 35 through the several compartments *c* and discharged at the bottom thereof through the branch pipes 5 and pipe 6 into the overflow and waste pipe 8. Each article or batch of articles in its passage through the machine 40 may by properly regulating the supply and flow of water and the speed of the conveyer be thus separately washed and rinsed by itself without being directly subjected to the dirty water with which other articles or 45 batches of articles are washed, thereby avoiding the unsanitary method of washing various articles or lots of articles together or with the same water, and at the same time admitting of continuously and successively 50 washing any number of articles or batches of articles separately.

The eccentrics 4 are set to move the plungers 2 downward as the pawl *v* turns the receptacle *e* an interval so that the clothes or the like contained in said receptacle will be lifted from the slats *g* on the lower side of the receptacle by the upward pulsation of water produced by the plungers and thus will be free to be advanced by the spiral conveyer *m* toward the discharge opening *l*.

The machine may be made with more or less compartments and the water supply connections arranged to deliver hot or cold water to more or less of the compartments 65 according to the capacity required and the

nature and condition of the articles to be washed. In short, various changes in the details of construction and arrangement of parts may be made within the scope of the invention without change in the principle or mode of operation of the machine. 70

The term "clothes" as used herein is intended to include not only wearing apparel and bedding, but also any fabrics or material which may be washed in a machine of this kind. 75

I claim:

1. In a washing machine the combination of a tank divided by partitions into a number of compartments which are provided with separate discharge connections, a receptacle extending through and communicating with the compartments of said tank and having provision at its ends for receiving and discharging the articles to be washed, means for moving such articles through said receptacle, and means for supplying water to said tank. 80

2. In a washing machine the combination of a tank having a number of compartments provided with discharge connections, means for moving articles to be washed along and in communication with said compartments, means for supplying water to said tank, and means for producing pulsations of the water through such articles as they pass through said tank along the several compartments. 90

3. In a washing machine the combination of a tank having intercommunicating washing and plunger compartments, a foraminated clothes receptacle within the washing compartment, and a plunger fitted in the plunger compartment and adapted to produce pulsations of water in the washing compartment through the clothes in said receptacle. 100

4. In a washing machine the combination of a tank having supply and discharge connections arranged to produce a current of water through the tank, means for conducting clothes through the tank, and means for producing pulsations of the water through the clothes as they pass through the tank. 110

5. In a washing machine the combination of a tank divided longitudinally by transverse partitions into compartments which are subdivided by longitudinal partitions into washing and plunger compartments; a clothes receptacle extending longitudinally through and communicating with the washing compartments, plungers fitted to work in the plunger compartments and adapted to produce pulsations of the water in the adjoining washing compartments, means for advancing clothes through said receptacle, 115 separate discharge connections opening from the lower parts of the several compartments of the tank, an overflow connection opening from the tank at the feeding end of the machine, and separate supply connections 120 125 130

adapted to deliver water into the several compartments of the tank.

6. In a washing machine the combination of a tank provided with discharge and over-flow connections opening from the lower part and one end thereof respectively, a clothes receptacle extending longitudinally through and communicating with said tank and provided with an internal spiral con-
10 veyer and with a feed opening in one end, means for producing pulsations of water within said tank and through said clothes receptacle, and a discharge opening at the other end, and a water supply connection arranged to deliver water into said tank.

7. In a washing machine the combination of a tank divided longitudinally by trans-verse partitions into compartments having separate discharge connections, a clothes re-

ceptacle arranged in said tank in commun- 20ication with said compartments and having a feed opening at one end and a discharge opening at the other end, means for advanc-ing clothes through said receptacle from its feed to its discharge opening, a valve-con-trolled hot water supply pipe opening into one or more compartments adjacent to the feeding end of the machine, and a separate valve-controlled cold water supply pipe opening into one or more compartments ad- 25 jacent to the discharge end of the machine.

In witness whereof I hereto affix my signature in presence of two witnesses.

FRANK WATERS VAN NESS.

CHAS. L. Goss,
ALICE E. Goss.

It is hereby certified that in Letters Patent No. 1,207,820, granted December 12, 1916, upon the application of Frank Waters Van Ness, of Milwaukee, Wisconsin, for an improvement in "Washing-Machines," errors appear in the printed specification requiring correction as follows: Page 3, claim 6, line 11, commencing with the word "means" strike out all to and including the word "receptacle," line 13, as now numbered; same page and claim, line 14, after the comma insert the words *means for producing pulsations of water within said tank and through said clothes receptacle;* and that the said Letters Patent should be read with these corrections therein that the same may conform to the record of the case in the Patent Office.

Signed and sealed this 16th day of January, A. D., 1917.
